UNITED STATES PATENT OFFICE.

CHARLES BERGER, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA.

PIVOTAL SASH MOUNTING.

Application filed May 10, 1921, Serial No. 468,288. Renewed September 4, 1924.

My invention relates to pivotal sash mountings and to hanger elements adapted for use in pivotally united pairs as hangers for mounting sashes in window frames, more especially for mounting pivoted ventilators in metallic sashes of a type which are to be permanently and immovably set in window apertures of buildings.

One aim of my invention is to standardize such hanger elements, so as to render them readily interchangeable, and capable, with equal facility, of being attached to the movable and immovable sections of the window structure.

Another object of my invention is to extend the scope of utility of such sash mounting appurtenances by enabling them to serve as weathering strips for overlapping the junctures between the sides of the pivoted sashes or ventilators and their frames or mountings when the sashes are in closed position. Or, to state the matter differently, my invention makes it possible to utilize the weathering itself for pivotally mounting a sash.

Other objects and attendant advantages of my invention will become readily apparent from the detailed description which follows:

In the drawings Fig. I is a perspective view of the exterior side of a typical metallic window sash provided with a pivoted ventilator, showing the manner in which hanger elements of my invention are applied.

Fig. II is a fragmentary view on an enlarged scale showing the details of one of the ventilator pivots.

Fig. III is an illustration similar to Fig. II showing the ventilator of the window in open position.

Fig. IV is a cross sectional view through one of the pivot axes of the ventilator, the plane of the section being indicated by the line IV-IV in Fig. II.

Fig. V is a detail sectional view across the line of juncture of the ventilator and its framing taken above the axis of pivoting as suggested by the arrows V-V in Fig. I, the ventilator being shown slightly open so as to avoid confusion as between the movable and immovable portions of the window sash.

Fig. VI is a view similar to Fig. V at a level below the pivot axis.

Fig. VII is a detail perspective view show-

ing clearly the construction of the pivot end of one of the hanger elements. 55

Fig. VIII is a perspective view of one of the special washers in the pivot joints shown.

Fig. IX is a fragmentary perspective view showing, to better advantage, the details of the sash pivot and the function of the special washers; and

Fig. X is an illustration generally similar to Fig. IX, but slightly modified in some details so that certain features of my invention may be more readily understood by 65 comparison.

Referring first to Fig. VII of the drawings, it will be observed that the hanger element or weathering member shown is in the form of a channel bar comprehensively indicated at 1 having weathering flanges 2 and 3 which are joined by a uniting web 4. Said bar may be constructed as a sheet metal stamping, bent to the form shown by pressing or in any other approved manner. A 70 portion of the wider flange 3 at the end of the bar is turned laterally to produce an integral projection 5 which is to serve as a pivot ear. Said pivot ear is offset somewhat from the plane of the web 4 as 75 clearly shown, for a purpose which will become obvious from further description, and provided with an aperture 6 for the accommodation of a suitable pivot bolt. The web 4 of the channel bar is continued so as to be co-extensive with the pivot ear 5, and preferably rounded as indicated at 7. Holes 80 such as shown at 8 are provided at intervals along the length of the bar for the reception of appropriate rivets whereby attachment to the window sash sections may be effected.

The narrower flange 2 of the channel is prolonged to form a tongue 9 which is divided from the web 4 by an incision 10. The elements 1 are, in practice, made in different lengths depending upon the proportions of the sashes which are to be hung. 85

As an example illustrative of the application of my invention in practice I have shown in Fig. I a metallic window sash "S" manufactured of standard cross sectional shapes, and of a type intended to be permanently and immovably set in a window aperture of a building. Certain of the muntins and mullions "M" of the sash are 100 interrupted as shown to afford a window 105

opening or frame "O" in which a separate pivoted ventilator sash "V" is mounted. In hanging such a ventilator I employ at each side, a pair of hanger elements one of my invention. One of said elements is fastened to the lower half of the portion of the mullion which borders the opening "O", and the other or companion element, is attached to the upper half of the perimetrical member "P" of the sash. As here shown, the hanger members 1, 1 are laterally affixed to the counterposed inner and outer edges of frame O and sash V, with their ears 5, 5 projecting laterally from said frame and sash. In effecting attachment to the ventilator, the web 4 of the first mentioned bar 1 is placed, pivot ear 5 lowermost, against the central web 11 of the perimetrical member "P" at the upper half of the latter and secured by rivets 12 as shown in Fig. V. Here it will be seen that flanges 2 and 3 of the bar respectively overlap the shoulder 13 and the end of the central web 14 of the muntin "M" of the stationary sash when the ventilator "V" is closed, thus affording a double weathering or seal which prevents passage of air or rain water. The companion hanger element 1 attached to the lower half of the portion of the mullion "M" of the stationary sash "S" which borders the side of the opening "O", see Fig. I, is secured in precisely the same manner as described above, rivets 15 being likewise employed in effecting attachment. The relation of the contacting parts is, however, here reversed, the flanges 2 and 3 of the bar cooperating in this instance with the shoulder 16 and web 17 of the perimetrical member "P" of the ventilator. The reversed arrangement, in the relation above noted, of the two complementary hanger elements 1, 1 constituting the pivot mounting at each side of the ventilator is necessary in order to permit swinging of the latter as will be clearly obvious from a cursory examination of Fig. I.

After the hanger elements 1 are properly secured to the members of the window sash structure, the organization is assembled, with the apertured ears 5—5 in sash and frame overlapping and pivot bolts 18 are passed through the registering ears 5—5 of the respective hanger elements as suggested in cross section in Fig. IV.

In the course of assembling, I preferably interpose in the hinge joints between the ears 5—5, special spacing washers such as shown at 19 in Figs. IV and VIII, similar in outline to the ears. These washers have straight, perpendicularly turned, portions 20, which are adapted to engage behind the offset shoulders of the ears 5, 5 so as to prevent relative rotation when the ventilator is operated.

From Fig. IX, it will be particularly noted that the special washers 19—19 correspond

in shape to the pivot ears 5—5 so as to be capable of completely filling the gap between them when the pivoted sash or ventilator is in closed position; thus preventing ingress of air and water through the pivot joint. This feature will perhaps be best understood by reference to Fig. X where I have shown, for the purposes of comparison, ordinary disk washers "W—W" instead of special washers 19—19. In this instance, it will be seen that the gap "G" is only partially closed, thus leaving quite a large opening which is entirely unprotected.

After the parts are assembled, as above noted, the tongues 9 of the lower elements 1 of the hanger units are bent inwardly as shown in Fig. II so they may be overlapped by the corresponding tongues 9 of the upper hanger elements carried by the ventilator,—this construction serving to afford an additional barrier against the entry of air and rain water.

Having thus described my invention, I claim:

1. A hanger element for pivoted window sashes in the form of a metallic bar having a channelled cross sectional configuration, and provided at one end with an integral lateral projection adapted to serve as a pivot ear.

2. A hanger element for pivoted window sashes in the form of a metallic bar having a channelled cross-sectional configuration, a portion of one of the flanges of the channel, at one end of the bar, being bent laterally to afford a pivot ear.

3. A hanger element for pivoted window sashes in the form of a metallic bar having a channelled cross-sectional configuration, a portion of one of the flanges of the channel, at one end of the bar being bent laterally to afford a pivot ear, and the other flange at the same end of the bar terminating in an extended tongue adapted to overlap a companion hanger bar.

4. A hanger element for pivoted window sashes in the form of a metallic bar having a channelled cross sectional configuration, the flanges of said bar being of different depths, and adapted to serve as weathering strips at the side edge of the window sash and the framing in which the sash is mounted, the deeper flange having a portion thereof, at one end of the bar, bent laterally to afford an integral pivot or hinge ear, and the narrower flange at the same end of the bar terminating in an extended tongue adapted to overlap a similar tongue of a companion hanger element.

5. A pivotal mounting for window sashes comprising weathering channels for the side edges of sash and window frame with overlapping ears comprising laterally bent portions of the weathering flanges, and pivots connecting said ears.

25

30

35

40

6. A pivotal mounting for window sashes comprising weathering channels for the side edges of sash and window frame with overlapping ears comprising laterally bent portions of the weathering flanges, washer means similar in outline to said ears interposed between them, and pivots connecting said ears and extending through said washers.
- 10 7. A pivotal mounting for window sashes comprising two counterpart, interchangeable hanger elements, each in the form of a channel bar having a portion of one of its flanges bent laterally in a plane offset slightly from that of the web of the channel bar to afford a shouldered pivot ear; a pivot bolt adapted to connect the pivot ears of the respective bar elements of the hanger; and apertured washers corresponding in shape to, and interposed between, the said pivot ears so as to completely fill an intervening gap, said washers having laterally turned edges adapted to engage behind the shoul-

ders of the aforesaid pivot ears to prevent relative turning.

8. The combination with a window frame and a sash therein, of hangers comprising sheet metal members laterally affixed to the contraposed inner and outer edges of frame and sash and having overlapping ear portions projecting laterally from said frame and sash and pivoted together.

9. The combination with a window frame and a sash therein, of hangers comprising sheet metal members laterally affixed to the contraposed inner and outer edges of frame and sash and having overlapping ear portions projecting laterally from said frame and sash and offset from the planes of the portions affixed to them as aforesaid, with pivots connecting said ear portions.

In testimony whereof, I have hereunto signed my name at Philadelphia, Penna., this thirtieth day of April 1921.

CHARLES BERGER.
